Charles H. Thompson

ATTORNEY

UNITED STATES PATENT OFFICE.

RILEY M. THOMPSON, OF SACRAMENTO, CALIFORNIA, ASSIGNOR OF ONE-HALF TO
HUGH A. WOODWARD, OF SACRAMENTO, CALIFORNIA.

MAIL-POUCH COLLECTOR.

Application filed August 8, 1924. Serial No. 730,883.

To all whom it may concern:

Be it known that I, RILEY M. THOMPSON, a citizen of the United States, residing at Sacramento, county of Sacramento, State 5 of California, have invented certain new and useful Improvements in Mail-Pouch Collectors; and I do declare the following to be a full, clear, and exact description of the same, reference being had to the accompanying drawings, and to the characters of reference marked thereon, which form a part of this application.

This invention relates to improvements in mail car equipment, and particularly to 15 the mail pouch collectors commonly used on the same.

In the collectors of the type now commonly used it often happens that due to various conditions and reasons the mail pouch is 20 not always accurately directed into the collector and held there. By reason of the inaccuracy in this regard the mail pouches are sometimes dropped or distorted or otherwise inefficiently handled.

25 It is the aim of my invention to provide a mechanism whereby when the pouch moves into the collector it will be instantly and immediately firmly and positively gripped therein with no possibility of the same being lost or distorted.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

40 In the drawings similar characters of reference indicate corresponding parts in the several views:

Fig. 1 is a front elevation of my improved pouch collector partly in section, and as it appears when standing in vertical inactive 45 position across the mail car door.

Fig. 2 is a top plan view of the same, also partly in section and showing the collector as it appears when moved to horizontal operative position across the door and after 50 my improved gripping arm has functioned to positively engage the mail pouch as it is received into the collector.

Fig. 3 is a perspective view of a bracket. 55 Referring now more particularly to the

characters of reference on the drawings, the numerals 1 and 2 designate the door posts of the mail car door. On the post 1 is the pouch collector supporting bracket 3, while on the post 2 is the bracket 4, the 60 main rod 5 being movable through the bracket 4 in the usual manner and the shank 6 thereof being movable through the bracket 3 and held in position by the usual cotter key 7.

65 The numeral 8 designates the handle of the collector used for turning the collector into horizontal position when it is to function in collecting the mail pouch.

In carrying out my improved invention 70 the handle 8 is on a housing 9 interposed between the rod 5 and its shank 6 and having side walls 10 and 11 respectively to which is suitably fastened the collecting arm or jaw 12.

75 Surrounding the shank 6 is a collar 13 having a pair of spaced finger members 14 engaging the neck 3^a of the bracket 3 to prevent the collar from turning.

An arcuate slot 15 is formed in the collar 80 13 at its lower side for a purpose as will presently appear. Interposed between the bracket 3 and housing 9 and turnable with the housing and surrounding the shank 6 is a rubber or other resilient collar 16 having 85 a longitudinal orifice 17 slidable in which is a pin 18.

This pin 18 is pivoted as at 19 to a dog 20 pivoted in the housing 9 and has a spring 21 normally holding it in contact with a 90 lever arm 22 of an arm 23 pivoted on the side wall 11 as at 24. A spring 25 is normally connected with the arm 22 and engages the member 12, the action of the spring being to act on the arm 22 to throw 95 the arm 23 toward the collector arm 12 whenever the dog 20 is released from engagement with the arm 22.

When the device is in normal inactive 100 position the dog 20 is engaged with the arm 22 holding the arm 23 spaced from the collector arm 12, as shown in Fig. 1. In this position all the parts can be turned up into operative position by the handle 8 to collect the pouch as the train proceeds. As the 105 collector arm 12 moves into contact with the pouch 26 the force of the impact moves the entire apparatus against the resilient collar 16 which is compressed. The pin 18, however, engages the collar 13 and cannot 110

be moved with the other parts and therefore as the other parts move against the collar 16 the dog 20 is actuated by the pin 18 to disengage it from the arm 22. Thereupon the spring 25 instantly acts against the arm 22 to drive the arm 23 toward the collector arm 12 and against the pouch 26 which has been engaged by such collector arm, and thus the pouch is pinched securely between the two members 12 and 23 and cannot be lost or dropped from the collector.

After the arm 23 has served its function it can be replaced manually into its inactive position, as described.

In order to prevent accidental disengagement of the dog 20 from the arm 22 when the collector mechanism is in its inactive position, as shown in Fig. 1, I have provided the slot 15. When the collector apparatus is in this position the pin 18 is immediately adjacent the slot 15 so that if there is any tendency of the mechanism to move against the resilient collar 16 the pin 18 will project into this slot and hence will not act to trip the dog 20.

A further preventative of untoward movement of the arm 23 is provided by means of a catch 27 situated on the post 2 just below the position taken by such arm 23 when it is moved downwardly into inactive position. Thus if the arm 23 should be accidentally released it will engage the catch instead of snapping against the collector arm 12, which might be disastrous if someone were to have their arm or fingers between the two at the time it happened.

The housing 9 would of course have a suitable covering which has not been shown in the drawings in order that the mechanism in the housing may be readily shown and described.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as set forth by the appended claims.

Having thus described my invention what I claim as new and useful and desire to secure by Letters Patent is:

1. In a mail pouch collecting mechanism, the combination with a rigid collecting arm, of a secondary and longitudinally movable arm normally spaced from the collecting arm, spring means tending to cause the secondary arm to move toward the collecting arm, means enabling said arms to be turned and moved longitudinally as a unit, means releasable with the longitudinal movement

of the arms for normally preventing the spring means from acting, and means whereby said last named means can only be released when the arms are turned to a pouch engaging position.

2. In a mail pouch collecting mechanism, the combination with a rigid collecting arm, of a secondary and longitudinally movable arm normally spaced from the collecting arm, spring means tending to cause the secondary arm to move toward the collecting arm, means enabling said arms to be turned and moved longitudinally as a unit, a detent normally engaging the secondary arm to prevent the spring from functioning, a member fixed with respect to the arms, and a pin mounted in connection with the detent parallel to the plane of longitudinal movement of the arms, and terminating adjacent one face of said member when the detent is set, means causing longitudinal movement of the arms toward said member when a pouch is engaged by the arms whereby the pin will be then held relatively stationary, and means whereby such relative movement between the arms and pin will cause the detent to be released, the fixed member having a socket with which the pin alines only when the arms are turned to a non-operative position whereby with any longitudinal movement of the arms when in such position the pin is free to move therewith.

3. In a mail pouch collecting mechanism, the combination with a rigid collecting arm, of a secondary arm normally spaced from the collecting arm, spring means tending to cause the secondary arm to move toward the collecting arm, means normally preventing such movement, means enabling the arms to be turned as a unit through a certain arc, and means whereby a longitudinal impact on the collecting arm will cause the secondary arm to move theretoward when said arms are in a pouch collecting position, but will prevent such movement when the arms are turned away from the pouch engaging position.

4. In a mail pouch collecting mechanism, the combination with a rigid collecting arm, of a secondary arm normally spaced from the collecting arm, spring means tending to cause the secondary arm to move toward the collecting arm, a detent normally preventing such movement, means enabling the arms to be turned as a unit through a certain arc, and means whereby the detent will be tripped to release the arm by a longitudinal impact imparted to the collecting arm only when the arms are turned to a pouch collecting position.

5. In a mail pouch collecting mechanism, a main support, mountings in which the support is held and capable of longitudinal movement therein, a collecting arm on the

support, means to hold the support normally against longitudinal movement, and means, controllable by the longitudinal movement of the support for clamping the mail pouch 5 against the collecting arm after it has been engaged by the latter and operable only when the collecting mechanism is moved to pouch engaging position.

6. In a mail pouch collecting mechanism, 10 a main support, mountings in which the support is held and capable of longitudinal movement therein, a collecting arm on the support, means to hold the support normally against longitudinal movement, means 15 controllable by the longitudinal movement of the support for clamping the mail pouch against the collecting arm after it has been engaged by the latter, such means including a pivoted and spring pressed second- 20 ary arm, a means normally holding same spaced from the collecting arm, the means for holding the support against normal lon- 25 gitudinal movement being adapted to give way when the mail pouch engages the collecting arm, and means for thereupon releasing the arm and allowing it to engage the pouch.

7. In a mail pouch collecting mechanism, 30 a pair of spaced brackets, a support mounted for longitudinal movement in the brackets, a fixed collecting arm on the support, a secondary arm pivoted relative to the support and having a spring pressed lever arm, a pivoted detent to engage the lever 35 arm to hold the secondary arm normally spaced from the collecting arm, a resilient member interposed between one bracket and the support, a pin connected to the detent projecting through the resilient member and 40 normally engaging the bracket with its free end, whereby when the collecting arm engages the pouch the impact will drive the support against the resilient member to con-

tract same, and thereupon the pin will operate to release the detent from the lever arm and the secondary arm will be spring pressed into engagement with the pouch. 45

8. In a mail pouch collecting mechanism a pair of spaced brackets, a support mounted for longitudinal movement in the brackets, a fixed collecting arm on the support, a secondary arm pivoted relative to the support and having a spring pressed lever arm, a pivoted detent to engage the lever arm to hold the secondary arm normally 50 spaced from the collecting arm, a resilient member interposed between one bracket and the support, a pin connected to the detent projecting through the resilient member and normally engaging the bracket with its free 55 end, whereby when the collecting arm engages the pouch the impact will drive the support against the resilient member to contract same, and thereupon the pin will operate to release the detent from the lever arm 60 and the secondary arm will be spring pressed into engagement with the pouch, the bracket having an arcuate slot at one point so that when the collecting arm is turned to inoperative position the pin will be alined with 65 such slot whereby to prevent undesired release of the secondary arm. 70

9. In a mail pouch collecting mechanism, 75 a main support, mountings for said support in which the latter is longitudinally movable, a collecting arm on the support, means controllable by such movement of the support for clamping a pouch against the collecting arm after said pouch has been engaged by the arm, and a resilient member between the support and one of the mountings for normally resisting any movement of the support. 80

In testimony whereof I affix my signature.

RILEY M. THOMPSON.
